(57) **CLAIM**

The ornamental design for a dental rack and dispenser, as shown and described.

DESCRIPTION

FIG. 1 is a top front perspective view of a dental rack and dispenser, showing my design;

FIG. 2 is a front elevation view thereof;

FIG. 3 is a top plan view thereof;

FIG. 4 is a rear elevation view thereof;

FIG. 5 is a bottom plan view thereof;

FIG. 6 is a left end elevation view thereof; and,

FIG. 7 is a right end elevation view thereof.

The broken line showing in the figures illustrates portions of the dental rack and dispenser and forms no part of the claimed design.
